UNITED STATES PATENT OFFICE.

ALFRED L. CASTLE, OF QUINCY, ILLINOIS.

STOVE.

1,108,336.

Specification of Letters Patent. Patented Aug. 25, 1914.

Application filed February 10, 1913. Serial No. 747,392.

To all whom it may concern:

Be it known that I, ALFRED L. CASTLE, citizen of the United States, residing at Quincy, in the county of Adams and State of Illinois, have invented new and useful 5 Improvements in Stoves, of which the following is a specification.

My present invention pertains to stoves, and more particularly heating stoves such 10 as are constructed with a view to burning soft coal; and it consists in the peculiar and advantageous stove hereinafter described and particularly pointed out in the claim appended.

15 In the drawings, accompanying and forming part of this specification: Figure 1 is a vertical section of a stove constructed in accordance with my invention. Fig. 2 is an elevation of the stove taken at a right angle to Fig. 1.

20 Similar numerals of reference designate corresponding parts in both views of the drawings.

The body 1 of my novel stove is preferably of sheet-metal, and in the same are arranged a grate 2 of conventional or any other suitable construction together with a fire pot 3 and a conical-shaped member 4 which forms a combustion chamber. At its 25 upper end the fire pot is provided with an outwardly-directed flange 5 which is disposed on and supported by lugs 6 carried by the body, there being by preference three of the said lugs employed. The conical-shaped member 4 is flanged at its lower end to rest on and be supported by the flange 5 of the fire pot, and at its lower end the said member 4 is formed with an inwardly projecting annular portion 7, V-shaped in cross-section, the lower inclined part of the portion 7 being provided with openings 7a. The upper end of the member 4 extends to the wall of the body 1, and there is an annular chamber 8 between the member 4 and the body 1, and a similar chamber 9 between the fire-pot 3 and the body, these chambers being in free communication with each other.

At 49 the body 1 is provided with an outlet for the products of combustion.

Carried by the body 1 and adjacent the upper portion of the chamber 8 is a draft regulator, and when the damper 10 of said regulator is positioned to admit atmospheric air to said chamber 8, it will be manifest 55 that the said air will be highly heated and

will be injected through the openings 7a into the combustion chamber and over the fire so as to increase the heating efficiency of the fuel; also, that a portion of the air admitted as stated to the chamber 8 will pass downward through the chamber 9 and up into the fuel at the lower end of the fire pot 3, so as to promote the combustion and increase the heating efficiency of the fuel. 60 It will further be noted that when the damper 10 is open and the ash door, hereinafter described, is closed, all of the air that enters the fire either at the top of the fire pot 3 or at the bottom thereof, will be superheated, and the hotter the stove becomes the more highly heated is the air supplied to the fire, with the result that there is complete combustion. Again when the damper 10 is closed and the ash door is opened, a 65 direct draft through the fuel is provided, and when the damper 10 and the ash door are both closed, the fire will go out. From this it follows that the ash door may be properly denominated the primary draft 70 regulator of the stove, and the damper 10 can be properly denominated the secondary draft regulator; also, that the fire can be absolutely and nicely controlled by regulating the extent to which the damper 10 is 75 opened.

In addition to the damper 10, which is preferably of the pivoted type, the draft regulator referred to comprises an apertured frame 11 that carries the damper 10 80 and is disposed at the outer side of the body 1, a cast-metal collar 12 being disposed at the inner side of the body 1, and connections 13, preferably bolts equipped with nuts, joining the frame, 11, the collar 12 and the 85 sheet-iron or sheet-steel of the body 1. By reason of the sheet iron or steel of the body 1 being interposed between the collar 12 and the frame 11, and the collar being drawn tight by bolts or the like, a perfectly 90 air-tight joint between the sheet-iron or 95 steel and the cast-iron elements is attained.

The frame 14 of the ash door 15 is connected to the body 1 in the same manner and for the same purpose as the frame 11 of the 100 draft regulator. This will be manifest by reference to Fig. 1.

Having described my invention, what I claim and desire to secure by Letters-Patent, is:

The herein described stove comprising a body, a conical-shaped member supported

in the body and separated therefrom by an annular space; said member being open at its lower and upper ends and having imperforate side walls, and said space being closed at its upper end and open at its lower end, a fire pot supported in the body below said member and open at its upper and lower ends and having an imperforate side wall; the fire pot being surrounded by 5 an annular space that is open at its lower and upper ends and is in communication with the first-named annular space, and the conical-shaped member resting on the upper end of the fire pot and being formed at 10 its lower end with an inwardly-projecting annular portion, V-shaped in cross-section,

the lower inclined part of the said V-shaped portion being provided with openings, an outlet for products of combustion leading from the body at a point above the conical-shaped member, a draft regulator connected with the body opposite the upper portion of the first-named annular space, and an ash door connected with the body at a point below the second-named annular space. 20 25

In testimony whereof I have hereunto set my hand in presence of two subscribing witnesses:

ALFRED L. CASTLE.

Witnesses:

J. W. THRASHER,
J. H. BOHON.
